UNITED STATES PATENT OFFICE.

OGDEN MINTON, OF GREENWICH, CONNECTICUT.

VELOCITY FLUID VACUUM SEAL, METHOD AND APPARATUS.

Original application filed November 30, 1920, Serial No. 427,436. Divided and this application filed July 25, 1922, Serial No. 577,364. Renewed February 17, 1926.

This application is a division of my co-pending application Ser. No. 427,436 filed November 30, 1920, Case L.

My invention relates to the method of treating materials in a vacuum, and more particularly to the method of protecting the opening or openings into the vacuum chamber through which opening or openings the material to be treated is introduced and 10 withdrawn from the chamber.

My invention relates more particularly to a vacuum seal maintained by the application of velocity head, i. e., the difference in pressure between the atmosphere and 15 vacuum being balanced by the velocity head of the sealing medium. Through this seal the material to be treated in the vacuum chamber is passed in any suitable manner.

My invention further relates more particularly to the method of drying sheet material, as a continuous web of paper either coming from the web end of a paper machine, or from a sizing vat, or from a coloring apparatus, coating or impregnating 25 machine, or printing machine or directly from a roll of wet paper.

My invention further relates to a vacuum apparatus, including a vacuum chamber having passages extending from the said vacuum chamber and open to the atmosphere. These passages are protected by 30 velocity fluid seals which prevent the admission of air into said vacuum chamber as the material to be treated is introduced 35 and withdrawn through said seals.

My invention further relates to employing any suitable fluid, in the velocity seals, which has no affinity for or deleterious effect upon the material to be treated in the 40 vacuum chamber. I may for example use mercury or an amalgam, or air, or steam or water or similar fluid having the characteristics above stated. In the case of water, if the material to be treated should, for 45 example, be a web of paper to be dried I may protect the web by endless rubber or waterproof felts or other similar guards.

My invention further relates to employ-

ing passages having restricted areas merging into progressively larger areas between the atmosphere and the interior of the vacuum chamber, forming in effect Venturi nozzles, through which the fluid of the velocity fluid seals flows. 50

My invention further relates to a vacuum chamber provided with entrance and exit openings having a plurality of restricted 55 passages similar to a plurality of Venturi nozzles connected in series.

My invention further relates to collecting the fluid of the velocity fluid seal and again using it in the seal, or if the fluid is steam, collecting and using it in the dryers, or using it to heat the building; or I may condense it or otherwise dispose of it. 60

My invention further relates to certain steps, and combinations of steps, also to certain elements and combinations of elements, whereby the method or processes herein described may be carried out, as well 70 as to certain details of construction, all of which will be more fully hereinafter described in the specification and pointed out in the claims.

I have shown in the drawings different 75 forms of apparatus which may be used to carry out my improved method, but it is to be distinctly understood that my invention is not to be confined to the particular form of apparatus, shown by way of illustration. 80

In the accompanying drawings the same reference numerals refer to similar parts in the several figures.

Fig. 1 is a diagrammatic view partly in 85 section of the simplest form of my invention;

Fig. 2 is a diagrammatic view similar to Fig. 1, except showing drying rolls or cylinders in the vacuum chamber; 90

Fig. 3 is a fragmentary vertical section of one form of vacuum chamber and velocity seal;

Fig. 4 is a vertical section of another modification in which a plurality of nozzles 95 are connected in series;

Fig. 5 is a detail vertical section showing a web of paper or similar material protected by endless rubber or waterproof felts or similar guards;

5 Fig. 6 is one of a plurality of ordinary steam radiators which may be connected to the chambers 11, 11 when steam or hot water is employed in the velocity seals.

10 I will describe the simplest form of my invention first, that shown diagrammatically in Fig. 1.

The vacuum chamber A has a vacuum maintained therein in any suitable manner 15 by connecting the pipe 1 with any suitable exhausting apparatus. This vacuum chamber has two passages 2, 2 open to the atmosphere. Through these passages the material to be treated in the vacuum chamber 20 A is introduced and withdrawn. Of course, if the passages were left unguarded the vacuum in the vacuum chamber A would be broken.

25 My invention broadly consists in guarding the passages to the atmosphere by velocity fluid vacuum seals, the velocity of the fluid being sufficiently high to prevent any air working past the velocity seal into the vacuum chamber.

30 In my invention suitable material may be introduced into and withdrawn from the vacuum chamber A through my velocity fluid seals 3, 3. It may be treated in any suitable manner within the vacuum chamber 35 A. It may be fed through the vacuum chamber continuously or not. I have shown by way of example the material in the form of a continuous web 7 which passes continuously through the vacuum chamber A

40 and the velocity fluid vacuum seals 3, 3. This web 7 may be dried in the vacuum chamber, or coated, colored, impregnated or treated in any other suitable manner, and may be fed into and out of the vacuum chamber in either direction as indicated by 45 the arrows.

These passages 2, 2 have restricted areas 4, 4. Connected with these restricted areas 50 are nozzles 5, 5. The area of the passages 2, 2 increases at 6, 6 adjacent the restricted areas 4, 4.

55 Fluid which has no affinity for or deleterious effect upon the web 7, or other material treated, is forced into the chambers 11, 11 through the nozzles 5, 5 at sufficient velocity to prevent air passing through the restricted area 4 and getting into the vacuum chamber A. The velocity required will depend on the vacuum maintained in the 60 vacuum chamber and the fluid used for the seal. Preferably I employ as near a perfect vacuum as I can maintain, usually about 28 inches of mercury.

65 Whatever fluid is used passes through the nozzles 5 with comparatively high velocity.

As the fluid reaches the portion 6 of comparatively large area its velocity is reduced. The passage 2 with its restricted area 4, nozzles 5 and portions of greater area 6 is in effect a Venturi type nozzle. The passage 70 2 is of course wide enough to permit the free passage of the widest web or other material 7 to be passed into and out of the vacuum chamber A.

The fluid which I employ for my velocity 75 fluid vacuum seal may be mercury or an amalgam or similar material, steam, water, air or similar fluid. If water is used as the fluid and the material treated is a web 7 of paper to be dried, then I may protect the 80 paper by rubber or other waterproof endless felts 16, 17, Fig. 5.

If air is used as the fluid of the seal it will be permitted to pass into the atmosphere. If water be used it may be collected 85 in the chamber 11 and drawn off by the pipe 12 to be used again or allowed to run to waste. If mercury or amalgam be used it would be collected in the chamber 11 and pass through the pipe 12 to be used again 90 as shown, for example, in the other figures of the drawings. If the fluid be steam, it would pass from chamber 11 through the pipe 12 to be used as the heating medium 95 in the steam drying cylinders or drums shown in the other figures of the drawings, or it may be used to heat the building by using one or more steam radiators 13, or the pipe 12 may be connected to a vacuum pipe 100 or condenser.

105 My invention is particularly adapted to be used in connection with drying sheet material in the form of paper, though it is to be distinctly understood that it is equally applicable to and covers drying sheet material in the form of textile fabrics, as for example, drying such fabrics after they have been washed or bleached or dyed, or otherwise treated by a liquid of some description.

110 I have shown my invention in connection with drying a web of paper in the other figures of the drawings.

115 In these other figures A is a vacuum chamber, in which I mount a plurality of drying drums or cylinders 14, 15, usually five being used as in my original application Ser. No. 427,436 of which this is a division. The wet web of paper 7 coming directly from the wet end of a paper machine, or from a coloring apparatus, coating machine, printing machine, or directly from the roll of wet paper, is fed into the vacuum chamber A. It is preferably, though not necessarily, received between the upper traveling 120 felt 16 and the lower traveling felt 17. These felts 16 and 17 with the interposed web 7 of paper or similar material are fed into the vacuum chamber A in any suitable manner, through a duplicate velocity seal 125 130

shown in Figs. 1, 3 or 4 of this application, or one of the forms of velocity seals shown in said parent application Ser. No. 427,436. The web 7 is then dried by passing over the 5 one or more drying drums or cylinders 14, 15, or dried in any other suitable manner in the vacuum chamber A.

I may not employ felts. When I do use them, I preferably arrange them as in said 10 parent application. As partly shown in Fig. 3, the upper felt 16 passes over the drying drum or cylinder 14 and meets the lower felt 17 after the latter has passed over the guide 18. Both felts 16 and 17 with the interposed web 7 pass over the drying drum or cylinder 15 and out through the exit passage, thence under the guide roll 19, the upper felt being led back over the vacuum chamber A to the entrance to said chamber, 15 while the lower felt 17 passes over the guide roll 20 and back to the same entrance passage under the vacuum chamber A.

In the form of my invention shown in Fig. 3, the restricted passage 21 is connected with nozzles 22, 22. The fluid 29, as for example, mercury is drawn from the felt roll housing 23 by the suction pipe 24 to the pressure pump 25, operated by the motor 26, and is forced through the pipe 27, into the nozzles 22, 22. As the mercury or similar material passes through the restricted area 21, it is moving with considerable velocity, which velocity is reduced as the portions of increased area 28 are reached. The restricted area connected with the passage of larger areas forms a Venturi type nozzle.

The liquid 29 of the seal is forced through the restricted area 21 of the passage with 40 just sufficient velocity to balance or slightly exceed the pressure of the atmosphere upon the liquid seal, which pressure if not counteracted, would cause the fluid of the seal to back up within the vacuum chamber.

45 The drying drums or cylinders 14 and 15, as well as the others not shown, are all preferably driven at the same speed that the web is traveling and are heated by steam in any suitable manner.

50 In Fig. 4 I have shown a further modification of my invention in which I employ a plurality of nozzles and restricted areas connected in series.

55 In this form of my invention the interior of the vacuum chamber A is connected with the felt roll housing 30 with a passage 31, and provided with different sets of nozzles 32, 33 and 34, and different restricted areas and enlarged areas all connected in series.

60 The mercury or similar material is taken from the barometric seal or reservoir 35 by the suction pipe 36 and is pumped by the pump 37 through the nozzles 34. The fluid has considerable velocity as it passes

through the restricted area 39, its velocity falling as it reaches the portion 40 of larger area. The suction pipe 41 of the second pump 42 is connected with the larger area 40 and gets supply from that area. It then 70 pumps the fluid through the nozzles 33 and the second restricted area 43, the velocity of the fluid again decreasing as it reaches the second large area 44. The suction pipe 45 of the third pump 46 is connected with the 75 large area 44 and pumps the fluid through the nozzle 32, the fluid then passing through the third large area 47 into the felt roll housing 30. The pumps may be driven in any suitable manner. I have shown them driven, 80 for example, by the motor 48 through the common shaft 49. The pipe 50 connects the felt roll housing 30 with the barometric seal or reservoir 35.

While I have shown three sets of nozzles 85 and restricted and enlarged areas, for purpose of illustration, it is of course to be understood that any number desired may be used.

While I preferably use mercury as the 90 fluid of my velocity fluid seals, it is of course to be understood that the liquid might be an amalgam or any other suitable material having no affinity for the web treated and no deleterious effect upon it, or any other 95 suitable fluid may be used.

The velocity of the fluid passing through the different restricted and enlarged passages shown in Fig. 4 is such as to balance or exceed the pressure of the atmosphere on the 100 liquid seal 51, which will prevent any of the liquid working back into the vacuum chamber A. Should the pressure exerted by the pumps momentarily not be sufficient to balance the atmospheric pressure on the liquid seal 51, a small quantity of the liquid 105 may work into the well 52. From this well 52, it will be immediately withdrawn by the pipe 53 extending into the reservoir 35 without breaking the vacuum in the vacuum chamber A. It will, therefore, be seen that in this form of my invention the reservoir 35 acts normally simply as a reservoir for the liquid to be pumped through the different restricted passages or Venturi type nozzles. It 110 is so located, however, that it also performs the function of a barometric seal, and will withdraw any liquid that might momentarily and accidentally work into the well 52.

115 My method possesses many advantages not present in processes heretofore used for many years in the drying of paper.

120 The evaporation process, which is characteristic of the so-called loft drying of paper, has many fully recognized disadvantages, 125 and yet it is used today and has been in use for many years. In this method the wet paper is taken from the paper machine, cut into sheets, hung on poles, carried to the drying room where it is subjected to hot air 130

at about 130° F. for about 48 hours, and when dry, each sheet is separately calendered. Although possessing the advantage of drying at comparatively low temperature, whereby the moisture is slowly evaporated, loft drying is obviously very inefficient and costly, because it requires many separate manipulations, is extremely slow, uses excessive floor space and wastes heat.

10 The process which is employed in the ordinary paper machine in common use, is likewise subject to many disadvantages. In such machine, the wet paper as it comes from the paper machine, is passed over many revolving cylinders, heated internally by steam to sufficiently high degree of heat, to raise the temperature of the water in the paper to 212° F., the atmospheric boiling point of water. It is customary to supply 15 the drying cylinders with steam at approximately 5.3 pounds gauge pressure, at which the steam has a temperature of 228° F., giving a difference of temperature (228°-212°) of only 16° F. With this slight difference 20 of temperature the transfer of heat is extremely slow, and hence it is necessary to employ many drying cylinders in board machines often one hundred, and in news print machines, forty or more.

30 Also due to convection and conduction losses, as well as those incident to leaks in the piping system and other inefficiencies, the heat actually required for atmospheric drying of a ton of wet paper, is very much 35 in excess of the theoretical requirement. The thermal efficiency of atmospheric drying by steam heated cylinders is therefore very low. Furthermore, the steam produced from boiling the water out of the paper is 40 driven off into the operating room, and although fans and exhausters are employed, at large expense for power and maintenance, the room atmosphere is so constantly saturated with moisture as to rust and ultimately 45 destroy all iron and steel materials, and produces an exceedingly disagreeable and unhealthy atmosphere in which to work. It is well known that the minimum temperature 212°, the atmospheric boiling point 50 of water, is positively injurious to, and results in oxidizing, the fibres of the paper, the strength of which is vastly improved when the paper is dried at lower temperatures, as in loft drying. This atmospheric 55 drying process requires large initial cost for cylinders, felts, and other necessary equipment, and extensive floor space, and results in the consumption of large amounts of power, and great cost for operation, maintenance and repairs.

60 In my improved vacuum drying method I contemplate maintaining within the chamber a vacuum of about 28" of mercury, in which water boils at 100° F., and supplying 65 the drying cylinders with steam at 5.3

pounds gauge pressure, producing a temperature of 228° F. The temperature difference between the temperature of the steam in the cylinders and that of the paper is therefore, 128° F. in my vacuum method, 70 or 8 times greater (16°×8=128° F.) than the temperature difference in atmospheric drying. In my improved method the paper dries approximately 8 times faster than in atmospheric drying, and I require only 75 about one-eighth the number of drying cylinders to dry paper at the same rate of speed. I am able to dry paper with 5 cylinders in the same time required of 40 cylinders drying at atmospheric pressure, resulting in great economies in cost of the machine, floor space and of necessary piping, felts, auxiliary equipment, and particularly in power and maintenance charges.

80 The thermal efficiency of my vacuum method is very much greater than that of the atmospheric cylinder drying heretofore in universal use for drying paper. Theoretically, it requires about 5287 pounds of steam to dry one ton of paper at atmospheric pressure, but to compensate for convection and conduction losses, and those due to leaks in the piping system, and other inefficiencies, it has been shown in practice that about 90 10,600 pounds are required.

95 In my method, using a vacuum of about 28", the convection, conduction and piping losses are exceedingly small and the total steam required to dry a ton of paper by my method is approximately 5200 pounds.

100 It is an established fact that paper dried at low temperatures is much stronger than when it is dried at the high temperatures used in paper machine atmospheric drying. Paper dried in a vacuum of 28", or at a temperature of about 100° F., as in my method, is very much stronger than paper dried at atmospheric pressure, when the steam in the driers is at 228° F. When paper is dried by my method, therefore, a 105 cheaper furnish or stock can be used and still produce a paper equal in strength to atmospheric dried paper, in which a higher grade furnish or stock is used. In making newsprint paper, I am able to dispense with 110 a considerable portion of the more expensive sulphite pulp, as this can be replaced with the cheaper ground wood pulp. By my method I also reduce the number of 115 breaks in the web as it passes over the cylinders.

120 Furthermore, in my method there is a great saving of heat (or steam) because the process is carried on in a vacuum chamber which acts on the principle of a thermos bottle, and the steam and vapors driven out of the wet paper are caught in the closed vacuum chamber, and conducted away to the condenser. The operating room is free 125 from steam, humidity and heat, and fans,

and exhausters are dispensed with. In the use of my method the apparatus is at all times operating under definite humidity, the control of the drying can be closely standarized, and the moisture content in the paper carefully regulated.

Some of the modern open air dryers are equipped with a blower system by which air, either heated or not, is blown through the 10 dryer section, which will lower the temperature at which the water is evaporated from the paper much below 212° F. and may, in some cases, reduce the temperature of evaporation as low as 180° F. or lower.

15 Having pointed out the many advantages of my method and apparatus over those heretofore used, it will be apparent that the use of my invention results in great economy in the initial cost of apparatus and 20 in large savings in cost of operation, maintenance and repairs.

Having thus described this invention in connection with illustrative embodiments thereof, to the details of which I do not 25 desire to be limited, what is claimed as new and what is desired to secure by Letters Patent is set forth in the appended claims.

What I claim is:—

1. The method of sealing a vacuum chamber having an opening for the admission of 30 material into said vacuum chamber to be treated consisting in preventing admission of air through said opening by causing fluid to flow through said opening against the pressure of the atmosphere.

2. The method of sealing a vacuum chamber having an opening for the admission of material into said vacuum chamber to be treated consisting in preventing admission 40 of air through said opening by causing liquid to flow through said opening against the pressure of the atmosphere.

3. The method of sealing a vacuum chamber having an opening for the admission of 45 material into said vacuum chamber to be treated consisting in preventing admission of air through said opening by causing mercury or amalgam or similar material to flow through said opening against the pressure of the atmosphere.

50 4. The method of continuously treating sheet material consisting in continuously feeding it into and out of a vacuum chamber through a fluid moving outwardly with sufficient velocity to have a pressure equal to or exceeding the pressure of the atmosphere and drying the sheet material in the vacuum chamber.

55 5. The method of continuously drying a web of wet paper consisting in continuously feeding the web into and out of a vacuum chamber through a fluid moving outwardly with sufficient velocity to have a pressure equal to or exceeding the pressure of the

atmosphere and drying the web of wet paper 65 in the vacuum chamber.

6. The method of continuously drying a web of wet paper consisting in continuously feeding the web into and out of a vacuum chamber through a liquid moving outwardly 70 with sufficient velocity to have a pressure equal to or exceeding the pressure of the atmosphere and drying the web of wet paper in the vacuum chamber.

7. The method of continuously drying 75 sheet material consisting in continuously feeding the sheet material in and out of a vacuum chamber through a fluid moving outwardly with sufficient velocity to have a pressure equal to or exceeding the pressure 80 of the atmosphere, and protecting the sheet material from contact with the fluid as it passes through it and drying the sheet material in the vacuum chamber.

8. The method of continuously drying a web of paper consisting in continuously feeding the web of paper into and out of a vacuum chamber through a fluid moving outwardly with sufficient velocity to have a pressure equal to or exceeding the pressure 85 of the atmosphere, protecting the web of paper from contact with the fluid as it passes through it and drying the web of paper in the vacuum chamber.

9. In a vacuum apparatus the combination 90 of a vacuum chamber having one or more restricted passages through which the material to be treated is passed, means to supply a sealing fluid moving outwardly through said restricted passage or passages 95 at a sufficient velocity to equal or exceed the atmospheric pressure, so that no air will work into the vacuum chamber and break the vacuum therein.

10. In a vacuum apparatus, the combination 100 of a vacuum chamber having entrance and exit openings through which the material to be treated in the vacuum chamber is adapted to pass each opening having a plurality of restricted passages similar to a plurality of Venturi nozzles, and means to supply fluid through said Venturi nozzles moving outwardly at sufficient velocity to equal or exceed the atmospheric pressure, 105 so that no air will work into the vacuum chamber and break the vacuum therein.

11. In a vacuum apparatus, the combination 110 of a vacuum chamber having entrance and exit openings through which the material to be treated in the vacuum chamber is adapted to pass each opening having a plurality of restricted passages similar to a plurality of Venturi nozzles, said plurality of Venturi nozzles connected in series, and means to supply fluid through said Venturi nozzles moving outwardly at sufficient velocity to equal or exceed the atmospheric pressure, so that no air will work into the vacu- 115

um chamber and break the vacuum therein.

12. The method of sealing a vacuum chamber having an opening for the admission of material into said vacuum chamber 5 to be treated consisting in preventing admission of air through said opening by passing fluid moving outwardly through said opening under sufficient velocity to have a pressure equal to or exceeding the pressure 10 of the atmosphere, and collecting the fluid and again using it to seal the openings into the vacuum chamber.

13. The method of sealing a vacuum chamber having openings for the passage 15 into and out of said chamber of material to be treated consisting in preventing admission of air through said openings by sealing said openings with a fluid subjected to a pressure outwardly greater than the 20 pressure inwardly and passing the material to be treated into and out of said vacuum chamber through said fluid.

14. The method of sealing a vacuum chamber having openings for the passage 25 into and out of said chamber of material to be treated consisting in preventing admission of air through said openings by sealing said openings with a liquid under pressure of the atmosphere and also artificial pressure, and passing the material to be treated into and out of said vacuum chamber through said liquid.

15. The method of sealing a vacuum chamber having openings for the passage 35 into and out of said chamber of material to be treated consisting in preventing admission of air through said openings by sealing said openings with a fluid subjected to a pressure outwardly greater than the 40 pressure inwardly, and passing the material to be treated into and out of said vacuum chamber through said fluid and protecting said material from contact with said fluid as the material is passed through it.

45 16. The method of sealing a vacuum chamber having openings for the passage into and out of said chamber of material to be treated consisting in preventing admission of air through said openings by sealing said openings with a liquid under pressure of the atmosphere and also artificial pressure, and passing the material to be treated into and out of said vacuum chamber through said liquid and protecting said material from contact with said liquid 55 as the material is passed through it.

17. In a vacuum apparatus the combination of a vacuum chamber provided with one or more restricted passages similar to 60 a Venturi nozzle and through which restricted passage or passages the material to be treated in the vacuum chamber is adapted to pass, and means to force a fluid outwardly through said restricted passage or 65 passages at sufficient velocity to prevent the

admission of air into the vacuum chamber.

18. The method of continuously drying a web of wet paper consisting in continuously feeding the web into and out of a vacuum chamber through mercury, amalgam or similar material, moving with sufficient velocity to prevent the admission of air into the vacuum chamber and drying the web of wet paper in the vacuum chamber. 70

19. The method of continuously drying a web of wet paper consisting in continuously feeding the web into and out of a vacuum chamber through a fluid which has no affinity for or deleterious effect upon said web, said fluid moving with sufficient velocity to prevent the admission of air into the vacuum chamber and drying the web of wet paper in the vacuum chamber. 75

20. The method of sealing an entrance or exit opening of a vacuum chamber through 80 which a wet web of paper is fed, said method consisting in forcing outwardly through the opening a fluid with sufficient velocity to prevent the admission of air into the vacuum chamber. 90

21. The method of sealing an entrance or exit opening of a vacuum chamber through 95 which a wet web of paper is fed, said method consisting in forcing outwardly through the opening a liquid with sufficient velocity to prevent the admission of air into the vacuum chamber.

22. The method of sealing an entrance or exit opening of a vacuum chamber through 100 which a wet web of paper is fed, said method consisting in forcing outwardly through the opening mercury, amalgam or similar material with sufficient velocity to prevent the admission of air into the vacuum chamber.

23. The method of sealing an entrance or exit opening of a vacuum chamber through 105 which a wet web of paper is fed, said method consisting in forcing outwardly through the opening a fluid with sufficient velocity to prevent the admission of air into the vacuum chamber and protecting the wet web of paper as it is fed through said fluid.

24. The method of sealing an entrance or exit opening of a vacuum chamber through 115 which a wet web of paper is fed, said method consisting in forcing outwardly through the opening a liquid with sufficient velocity to prevent the admission of air into the vacuum chamber and protecting the wet web of paper as it is fed through the liquid.

25. The method of sealing an entrance or exit opening of a vacuum chamber through 125 which a wet web of paper is fed, said method consisting in forcing outwardly through the opening mercury, amalgam or similar material with sufficient velocity to prevent the admission of air into the vacuum chamber and protecting the wet web of paper as it is fed through the mercury amalgam or similar material. 130

26. In a vacuum apparatus, the combination of a vacuum chamber having entrance and exit openings through which the material to be treated in the vacuum chamber is adapted to pass, each opening having a plurality of restricted passages similar to a plurality of Venturi nozzles, and means to supply fluid through said Venturi nozzles.
- 5 27. In a vacuum apparatus the combination of a vacuum chamber having entrance and exit openings through which the material to be treated in the vacuum chamber is adapted to pass each opening having a plurality of restricted passages similar to a plurality of Venturi nozzles, said plurality of Venturi nozzles connected in series, and means to supply fluid through said Venturi nozzles.

10 27. In a vacuum apparatus the combina-
